United States Patent Office

Des. 220,107

Patented Mar. 9, 1971

220,107

RECORDING SYSTEM OPERATIONAL PANEL

Edgar F. Trombly, Grosse Pointe Farms, Mich., assignor
to Scanfax Systems Corporation, New York, N.Y.

Filed Oct. 1, 1969, Ser. No. 19,368

Term of patent 14 years

Int. Cl. D14—01

U.S. Cl. D26—14

FIG. 1 is a top plan view of the design for a recording system operational panel;

FIG. 2 is a front elevational view thereof;

FIG. 3 is a left-side elevational view thereof;

FIG. 4 is a right-side elevational view thereof;

FIG. 5 is a rear elevational view thereof; and

FIG. 6 is a perspective view thereof.

I claim:

The ornamental design for a recording system operational panel, as shown.
